[57] **CLAIM**

The ornamental design for a combined light for a motorcycle helmet and controlling signal transmitter therefor, as shown and described.

DESCRIPTION

FIG. 1 is a front, top and side perspective view of the combined light for a motorcycle helmet and controlling signal transmitter therefor showing my new design, the two portions of the device being connected by over-the-air communications;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom plan view thereof.

The transmitter is mounted on the motorcycle using the ring clip shown to receive power from the motorcycle, while the light emitting element is mounted on a motorcycle helmet on the curved rear surface thereof. The two elements communicate via over-the-air means.

FIG. 2

FIG. 3

FIG. 4

FIG. 5

FIG. 6

FIG. 7
